US00D957081S

(12) United States Design Patent (10) Patent No.: US D957,081 S
Chen et al. (45) Date of Patent:  Jul. 5, 2022

(54) LAWN REFUSE BAG INSERT

(71) Applicant: Pratt Corrugated Holdings, Inc.,
Brookhaven, GA (US)

(72) Inventors: Shifeng Chen, Newport News, VA
(US); Greg Sollie, Sharpsburg, GA
(US); Jamie Waltermire, Peachtree
City, GA (US)

(73) Assignee: Pratt Corrugated Holdings, Inc.,
Brookhaven, GA (US)

() Term: 15 Years

(21) Appl. No.: 29/809,463

(22) Filed: Sep. 28, 2021

Related U.S. Application Data

(63) Continuation of application No. 29/715,742, filed on Dec. 4, 2019, now Pat. No. Des. 935,124.

(57) CLAIM

We claim the ornamental design for a lawn refuse bag insert, as shown and described.

DESCRIPTION

FIG. 1 is a top perspective view of a lawn refuse bag insert.

FIG. 2 is a left-side elevation view thereof.

FIG. 3 is a right-side elevation view thereof.

FIG. 4 is a front elevation view thereof.

FIG. 5 is a rear elevation view thereof.

FIG. 6 is a top plan view thereof; and,

FIG. 7 is a bottom plan view thereof.

The broken lines in the figures show portions of the lawn refuse bag insert, which form no part of the claimed design.

1 Claim, 5 Drawing Sheets
